Patented Feb. 24, 1914.

UNITED STATES PATENT OFFICE.

THOMAS N. BIRCH, OF KANSAS CITY, MISSOURI.

CIRCUIT-CONTROLLING LOCK.

1,088,648.

Specification of Letters Patent. Patented Feb. 24, 1914.

Application filed September 30, 1912. Serial No. 723,137.

To all whom it may concern:

Be it known that I, THOMAS N. BIRCH, a citizen of the United States, residing at Kansas City, in the county of Jackson and 5 State of Missouri, have invented a certain new and useful Improvement in Circuit-Controlling Locks, of which the following is a specification.

My invention relates to improvements in 10 circuit-controlling locks. It is particularly adapted for use in controlling the igniting circuit of an automobile so as to prevent the running of the machine by an unauthorized person.

15 My invention is particularly adapted to locks provided with tumblers.

In the accompanying drawings which illustrate the preferred form of my invention—Figure 1 is a vertical sectional view 20 on the line *a*—*b* of Fig. 2 showing a tumbler lock of the "Yale" type, the key being shown inserted and the contact moving device forced inwardly thereby but not turned into operative position. Fig. 2 is an 25 outer end view of the lock. Fig. 3 is a horizontal section on the line *c*—*d* of Fig. 1. Fig. 4 is a cross section on the line *e*—*f* of Fig. 1. Fig. 5 is a cross section on the line *g*—*h* of Fig. 1. Fig. 6 is an arcuate 30 section on the line *i*—*j* of Fig. 5, a portion only of the plate 27 being shown in section. Fig. 7 is a diagrammatic view of a circuit containing my improved lock.

Similar characters of reference designate 35 similar parts in the different views.

1 designates the casing of the lock which is preferably of cylindrical form provided at its outer end with a head 2.

Within the barrel or body 1 and secured 40 against turning therein by any suitable means such as a screw 3, is a ring 4 provided with two rows of radial holes 5 and 6, said two rows being arranged at right angles to each other as shown in Fig. 4. Slidably 45 mounted in the holes 5 are tumblers 7 which are adapted respectively to enter radial holes 8 which are provided in a rotary member 9 mounted in the ring 4. In the holes 6 are mounted slideable tumblers 10 which are 50 adapted to cooperate respectively with the tumblers 7 when the member 9 is in the position shown in Fig. 1, and with tumblers 11 which are mounted in the holes 6 when the member 9 has been turned at right angles 55 to the position in which it is shown in Figs.

1 and 4. Coiled springs 12 are mounted in the holes 5 and have their outer ends bearing against the casing 1 and their inner ends against the tumblers 7. Similar coiled springs 13 are similarly mounted in the 60 holes 6 and effect a similar function with respect to the tumblers 11.

The member 9 has extending longitudinally through it and communicating with the holes 8, a key hole 14, which is adapted 65 to receive a key 15, shown in Figs. 1, 3 and 4.

Secured in the rear end of the casing 1 is a head 16, which is preferably of insulating material such as hard rubber or vulcanized fiber, and which is provided with 70 a central horizontal tubular extension 17 provided on its upper side with a longitudinal slot 18 which extends rearwardly from the forward end of the extension 17 and communicates with a lateral slot 19 75 which is located at the rear end of the slot 18.

Slidably mounted in the extension 17 is a key operated device 20 which is provided with a laterally extending arm 21 normally 80 extending through and slidably mounted in the slot 18 and adapted to enter the slot 19 when the member 20 has been forced by the key 15 to the position shown in Figs. 1 and 3. The forward end of the member 20 is 85 provided with a slot 22 which is adapted to receive the key 15. A coiled spring 23 mounted in the extension 17 bears against the rear side of the member 20 for normally forcing said member into the slot 18. 90

Extending through the head 16 is a binding post 24 to which is secured at the inner side of the head 16 a contact 25 adapted to be struck by but normally separated from a contact 26 carried by a spring 27 which is 95 of metal and which is secured to a binding post 28 which extends through the head 16.

The arm 21 has mounted on it, preferably rotatably, a disk 29 of insulating material, such as hard rubber and which is adapted, 100 when the key 15 and arm 21 are turned to positions at right angles to that shown in Fig. 1, to strike the spring 27 and force it to a position in which the contact 26 will strike the contact 25 for the purpose of closing the circuit in which said contacts are located. 105

The contacts 25 and 26 may be located in a circuit containing any desired mechanism. If located in a circuit containing a spark 110

producing coil of the automatic type, a circuit such as is shown in Fig. 7 may be employed. Referring to this figure, 30 designates an electric battery having one pole 5 connected by a conductor 31 to the binding post 24. The other pole is connected by a conductor 32 with a contact 33 which is adapted to be normally in contact with a spring metal strip 34 secured at one end to 10 a post 35 and having mounted on its other end an armature 36 located in the field of a core 37 of an induction coil the primary winding 38 of which is connected at one end to the post 35 and at its other end to a conductor 39 which is connected to the binding post 28. The secondary winding 40 of said induction coil has its ends respectively connected to conductors 41 and 42 which in turn are respectively connected to two contacts 43 and 44, which are separated from each other, but which are near enough to each other to permit the passage of currents which traverse the secondary circuit. When the spring 27 is moved into position in 25 which the contacts 25 and 26 will be against one another, the primary circuit will be closed until the core 37 by attracting the armature 36 breaks the circuit at the contact 33. The operation of this automatic 30 circuit breaking mechanism is well known and will need no further description. While the contacts 25 and 26 are against one another the current will pass from the battery 30 through conductors 31, binding 5 post 24, contact 25, contact 26, spring 27, binding post 28, conductor 39, winding 38, post 35, spring 34, contact 33, and conductor 32 back to the battery 30. The rapid breaking of the primary circuit will produce 40 a series of currents in the secondary circuit thereby effecting the production of sparks between the contacts 43 and 44. It will be understood that these sparks may be employed to ignite charges in an explosive en- 45 gine not shown.

In the operation of my invention the key 15 is inserted through the key hole 14 and into the slot 22 of the member 20, said member being forced against the pressure 50 of the spring 23 to the position shown in Fig. 1, in which position the arm 21 will be in register with the slot 19. If the key 15 is the proper key for the lock it will have forced the tumblers 10 to the position shown 55 in Fig. 1, in which position said tumblers and the tumblers 7 will have their abutting ends coincident with the periphery of the rotary member 9. This position of the tumblers will permit rotation clockwise of the 60 member 9 by the key 15 to a position in which the tumblers 10 will register respectively with the tumblers 11 which correspond to the tumblers 7. At this time the roller or disk 29 will have forced the spring 65 27 to the closed position with the contacts

25 and 26 against each other. The key 15 may now be withdrawn, upon which the tumblers 11 will enter the holes 8 and prevent the turning of the member 9. To break the primary circuit it is but necessary now to reinsert key 15 in the key hole 14 and turn the key counter-clockwise to the position shown in Fig. 1. If the key 15 be now withdrawn, the tumblers 7 will enter the holes 8 and will lock the member 9 against turning, the primary circuit at this time being open.

I do not limit my invention to the structure described and shown as modifications, within the scope of the appended claims may be made without departing from the spirit 80 of my invention.

Having thus described my invention, what I claim and desire to secure by Letters Patent, is:—

1. A circuit controlling lock provided with circuit controlling means, a key operated device movable longitudinally and laterally by a key and when moved laterally to the proper position operating the circuit controlling means, means for yieldingly holding said device from longitudinal movement, and means for holding said device from laterally moving until it has been moved longitudinally to a predetermined 95 position.

2. In a circuit controlling lock, circuit controlling means, a tubular holder having a longitudinal slot and a lateral slot intersecting the longitudinal slot, a key operated device slideable in the longitudinal slot to and from a position in which it will register with the lateral slot and movable in the lateral slot by a key to a position in which it will operate the circuit controlling means, 100 and yielding means for normally moving the said device in said longitudinal slot to a position in which it will not register with the lateral slot.

3. In a circuit controlling lock, circuit 110 controlling means, a device movable longitudinally and laterally by a key inserted in the lock and when moved laterally to a predetermined position operating the circuit controlling means, means for holding the device from lateral movement until it has been moved longitudinally to a certain position, a rotary member having means for receiving and being rotated by said key simultaneously with the lateral movement 115 of said device, and means releasable only by a key fitted to the lock for holding said rotary member from turning from either of two positions to which it may be turned.

4. In a circuit controlling lock, circuit 120 controlling means, a device movable longitudinally and laterally by a key inserted in a lock and when moved laterally to a predetermined position operating the circuit controlling means, means for holding the de- 125

vice from lateral movement until it has been moved longitudinally to a predetermined position, yielding means for holding said device from being moved longitudinally to said position, a rotary member having means for receiving and being rotated by said key simultaneously with the lateral movement of said device, and means releasable only by a key fitted to the lock for holding said rotary

member from turning from either of two 10 positions to which it may be turned.

In testimony whereof I have signed my name to this specification in presence of two subscribing witnesses.

THOMAS N. BIRCH.
